UNITED STATES PATENT OFFICE.

HERBERT RICHARD WATTS, OF BROOKLANDS, ENGLAND.

PHOTOGRAPHIC-PRINTING APPARATUS.

SPECIFICATION forming part of Letters Patent No. 780,844, dated January 24, 1905.

Application filed November 18, 1904. Serial No. 233,338.

To all whom it may concern:

Be it known that I, HERBERT RICHARD WATTS, optician, a subject of the King of Great Britain, residing at Arrandale, Arran 5 avenue, Brooklands, in the county of Chester, England, have invented new and useful Improvements in Photographic-Printing Apparatus, of which the following is a specification.

10 My invention relates to improvements in apparatus for photographic printing for the reproduction of tracings or semitransparent drawings on sensitized material by either sunlight, electric-arc lamp, or other suitable artificial light.

15 The principal objects of my improvements are to provide an apparatus that will reproduce tracings of any length and to simplify and expedite the production of photo copies 20 of smaller tracings.

A suitable apparatus constructed and adapted to accomplish the above objects consists of a plate, preferably flat and made of glass or other suitable transparent material, fixed in a 25 framework of any convenient character. (The plate may be fixed horizontally, vertically, or at any suitable angle.) In conjunction with this plate I employ a series of rollers, preferably rubber-covered, between which the tracing or semitransparent drawing and the sensitized material are together fed. The rollers are so constructed that they can be rotated in unison at varying speeds either by hand or power and are so arranged that when rotating 30 they press, with a pressure which can be adjusted, the sensitized material and tracing against the transparent plate and at the same time feed the plan and the material across the plate. Guide rollers or plates are arranged 35 at the edge of the transparent plate to feed the sensitized material between the aforesaid series of rollers and transparent plate.

In the accompanying three sheets of drawings, Figure 1 is a front elevation, and Fig. 2 40 an end sectional elevation, of my improved photographic-printing apparatus. Fig. 3 is a detail view, on a larger scale, of part of Fig. 2.

In the views, *a* designates the frame of the apparatus, *b* the flat plate of glass fixed diag-

onally therein, and *c* the series of rubber-covered rollers. Each alternate roller *c* has a sprocket-wheel *d* fixed on one end, and the remaining rollers *c* have similar sprocket-wheels fixed on their other ends, and the two series of sprocket-wheels *d* are driven by a pair of 50 chains *e* from sprocket-wheels *f*, fixed one near each end of a cross-shaft *g*, which is driven by gears *h* *i* from a worm *j*, fixed on a shaft *k*. The shaft *k* may be turned by hand or may be driven by means of a band or 55 belt *l* and a stepped pulley *x* from any convenient motor. The tracing *m* to be reproduced is batched on a roller *n* and is led between a glass or other guide-plate *y* and the first of the rubber-covered rollers *c* and then 60 between the rubber-covered rollers *c* and the glass plate *b* to a driven batching-roller *o*. In like manner the sensitized material *p* is led from the batching-roller *q* to the driven batching-roller *r*, which, with the other batching- 65 roller *o*, is driven at the same surface speed as the rubber-covered rollers *c* by means of a chain *s* and sprocket-wheels from the cross-shaft *g*. Each rubber-covered roller *c* has its 70 bearings in slide-blocks *t*, and these blocks *t* are adjusted, by means of screws *u*, to regulate the pressure of the rollers *c* against the plate *b*. In place of the gearing described 75 any other suitable arrangement of gearing may be adopted for driving the rubber-covered rollers *c*.

In using the apparatus the tracing or semitransparent plan *m* to be reproduced from the roller *n*, together with the sensitized material *p* from the roller *r*, is fed between the series of 80 rubber-covered rollers *c* and the transparent plate *b*, and so traveled across the plate *b*.

By regulating the speed at which the rollers rotate sufficient time is obtained for the exposure of the sensitized material to the rays 85 of light passing through the transparent plate *b*. The light may be sunlight when obtainable or any suitable artificial light, such as that of electric-arc lamps, mercury-vapor tubes, or the like. The operation is thus continuous, and the length of the reproduction is 90 unrestricted.

Small tracings or the like may be fed

through in the same manner one after the other without altering the apparatus.

What I claim, and desire to secure by Letters Patent of the United States, is—

5 In photographic - printing apparatus the combination with a transparent plate fixed in a suitable framework, of a series of rubber-covered or equivalent rollers placed in proximity to each other and to said plate, and means

for driving and adjusting the same, substantially as herein set forth.

In testimony whereof I have signed my name to this specification in the presence of two subscribing witnesses.

HERBERT RICHARD WATTS.

Witnesses:

HENRY BEINOUILLI BARLOW,
HERBERT ROWLAND ABBEY.
